CLAIM

The ornamental design for a plush stuffed animal, as described and shown.

DESCRIPTION

FIG. 1 is a front perspective view of a plush stuffed animal illustrating my design;

FIG. 2 is a front elevation view thereof;

FIG. 3 is right side elevation view thereof;

FIG. 4 is a left side elevation view thereof, the right side elevation view being identical in appearance;

FIG. 5 is a bottom plan view thereof;

FIG. 6 is a top plan view thereof; and,

FIG. 7 is a rear view thereof.
